Patented Sept. 13, 1921.

FIG. 3

George S. Weinert Inventor.

By *W. H. Stewart*

Attorneys

UNITED STATES PATENT OFFICE.

GEORGE S. WEINERTH, OF READING, PENNSYLVANIA.

PRINTING ATTACHMENT FOR KNITTING-MACHINES.

1,390,660.

Specification of Letters Patent. Patented Sept. 13, 1921.

Application filed November 23, 1920. Serial No. 425,955.

To all whom it may concern:

Be it known that I, GEORGE S. WEINERTH, a citizen of the United States, residing at Reading, in the county of Berks and State 5 of Pennsylvania, have invented certain new and useful Improvements in Printing Attachments for Knitting-Machines, of which the following is a specification.

My invention consists in a printing attachment for knitting machines, which is 10 adapted to automatically print determined markings upon each of a series of consecutively produced knitted articles, and which is fully described in connection with 15 the accompanying drawing and the novel features thereof clearly defined in the claims.

Figure 1 is a plan view of the attachment; coöperative portions of a knitting machine to which it is applicable, and a cross-section 20 of the fabric, being indicated in dotted lines.

Fig. 2 is a sectional elevation mainly on the line 2—2 of Fig. 1, with the relative positions of knitting machine parts and of the fabric again indicated.

Fig. 3 is a partial end view with the fixed platen arm broken away and the inking device removed.

The directly coöperating parts of a knitting machine in connection with which my 30 invention is employed, are the needle cylinder indicated at *a*, and the pattern wheel *b* suitably mounted in the machine frame *c* and chain driven as usual to automatically control the knitting as required; these parts 35 being shown in the relation commonly employed in hosiery ribbers. The fabric *d* represents a connected series of tops, as ordinarily knitted on such machines and as passing through the fabric-way 5 of the attachment 40 to the usual take-off rolls *e*.

These hosiery ribbers, which knit a continuous string of hosiery tops to be subsequently cut apart for separate use in completing the stockings, are commonly employed in large numbers; and the particular 45 purpose of my invention is to provide for automatically marking each top produced so as to identify the particular machine which produced it, so that in case of any defect the cause thereof may be quickly determined and corrected.

The frame of the printing attachment is formed with attaching arms 6, 6 adapted to be rigidly secured, as indicated, to the knitting machine frame *c*; with a slide-way 55 bracket 7 extending at right angles to the

axis of the needle cylinder and having a fixed-platen extension arm 8 spaced apart from the end of the slide-way portion of bracket 7 so as to provide the vertical fabric-way 5; and with vertical supports 9, 9 forming bearings for the lever mechanism employed to operate the reciprocative bed member 10 in the slide-way of the bracket.

The reciprocative bed member 10, which is 60 suitably guided in the bracket slide-way, is provided at its forward end with an impression plate or type 11 adapted to effect any desired marking on the interposed portion of fabric *d*, when the member 10 forces it 65 outward against the fixed platen arm 8.

This movement is automatically imparted to the member 10 at determined intervals, corresponding with the fixed length of each top, by action of the pattern wheel *b* upon 70 the operating lever mechanism carried by the supports 9, 9 of the attachment frame. As shown this mechanism comprises a horizontal shaft 15 mounted in said supports and provided with a fixed operating arm 16; 75 the spring-pressed pivoted end portion 17 of the latter being arranged in the path of a projection or pin 18 on the pattern wheel so as to cause a rocking movement of the shaft 15 at a determined time in each rotation of the pattern wheel, and consequently 80 at a determined position of each knitted top produced. This rocking movement of shaft 15 is transmitted to the reciprocative bed member 10 through a link 20 pivotally connected to lugs 21 on said member; this being effected as shown through an intermediate lever shaft 22 also mounted in said supports 9, 9 and arranged to receive a rocking 85 movement from an arm 24 on said operating shaft 15, and to transmit the same to the member 10, as desired through a fixed arm 25 on the shaft 22 and said pivoted link 20.

To provide for automatically inking the 100 impression end of the reciprocative member 10 after the making of each impression, I employ an inking device 30, pivotally secured at 31 to lugs 32, 32 on the slideway bracket 7, and having an end portion 33 thereof depending below said pivoted connection 31 so as to be operatively engaged by the reciprocative member 10; the latter being provided on its upper surface with spaced offsets 35, 36 forming between them a recess for said 105 depending end 33 of the inking device, so that the latter is caused to swing reversely 110

with corresponding movements of the member 10. The inking end 39 of the device is thus swung into inking contact with the impression end of the member 10 during each 5 retracting movement of the latter, and is swung out of the way, as indicated in dotted lines, during each forward movement of the latter. A stop spring 40 is shown to limit the upward swing of the inking device.

10 The pattern wheel 7 being arranged to make one rotation for each knitted top produced, its projecting pin 18 will strike the end 17 of the properly adjusted lever arm 16, and after taking up the limited spring 15 movement of said end 17 will turn the lever shaft 15, and through connected arms 24, 25, shaft 22 and link 20, will press forward the reciprocative bed member 10 in the guide-way bracket 7. The offset 35 of the latter, 20 pressing against the depending end 33 of the inking device 30 will swing the latter upward to the dotted position indicated, leaving the inked impression end of the member 10 free to press the fabric in fabric-way 5 against the fixed platen arm 8 and impart the desired marking—ordinarily the particular number of the machine to which the attachment is applied. When the pin 18 passes the lever arm 16 the member 10 is 30 withdrawn by a spring 41, and offset 36 of the member 10 throws the end 39 of the pivoted inking device 30 into inking contact with the impression end 11 of said member; while the lever arm 16 is returned to normal 35 position for a repeat—operation by the pattern wheel. If a defect appears in any product of a series of machines provided with the attachment, the particular machine in which such defective product was made is at once 40 identified by the marking.

The preferred construction of my attachment which is specifically set forth may obviously be modified within the scope of the invention as defined in the claims.

45 What I claim is:

1. In combination with a knitting machine having a needle cylinder and a pattern wheel; a fabric-printing mechanism comprising an attaching frame having operat-

ing-lever supports and a slide-way bracket 50 forming a passage-way for the produced fabric, a reciprocative bed member in said slide-way, and lever devices for projecting said member including a tensioned arm arranged in the path of said pattern wheel 55 having limited independent movement.

2. A fabric-printing mechanism for circular knitting machines, comprising an attaching frame having operating-lever supports and a slide-way bracket with an extension 60 forming a fabric-way, a reciprocative bed member in said slide-way, a pivoted inking device, means carried by the bed member operating to positively swing the inking device to operative and inoperative positions 65 incident to the retracting and advancing movements, respectively of the bed member and lever mechanism for operating said reciprocative platen member.

3. A fabric-printing mechanism for circular knitting machines, comprising an attaching frame having operating-lever supports and a slide-way bracket, a stationary arm arranged at the end of the slide-way bracket forming a fabric-way, a reciprocative bed member in said slide-way, an inking device pivoted to said bracket and operatively engaged by said reciprocative platen member, and lever mechanism for operating the latter.

4. A fabric printing mechanism for circular knitting machines comprising an attaching frame having operating-lever supports and a slide-way bracket with an extension forming a fabric way, a reciprocative bed member in said slide-way, a lever mechanism for operating said reciprocative platen member, a pivoted inking device, means carried by the bed member operating to positively swing the inking device to operative and inoperative positions incident to the retracting and advancing movements, respectively, of the bed member, and means to resiliently stop the movement of the pivoted inking device during its return to inoperative position.

In testimony whereof I affix my signature.
GEO. S. WEINERTH.
